WALTER J. SCOTT, OF WOONSOCKET, RHODE ISLAND

STOP MOTION

Application filed August 17, 1929. Serial No. 386,616.

The present invention relates to stop motions for textile machinery, and has particular reference to electrically operated stop devices positioned between the draft rolls and the 5 spindles.

One object of the invention is to provide a stop motion which will operate whenever the tension on a sliver slackens.

Another object is to provide a stop motion 10 operating whenever a slub or imperfection of greater width than the width of the sliver occurs.

A further object of the invention is to position a spacer frame between the draft rolls 15 and the spindle with a spacer bar in said frame normally resting on the sliver which passes through the frame, and movable by abnormal thickening of a sliver or by pressure of a sliver or of a slub therein, to operate 20 the stop motion.

Further objects and advantageous features 25 of my invention will be readily apparent from the detailed description following, in conjunction with the accompanying drawings, and will be particularly pointed out in the appended claims.

In the drawings:

Fig. 1 is a view partly in section, showing 30 the movement of a sliver through the gill box;

Fig. 2 is a view in perspective showing several slivers passing through the spacer frame in parallel relationship;

Fig. 3 is an elevation, partly in section and 35 partly broken away, showing the mounting of the spacer bar and of the electrical contact member on the spacer frame;

Fig. 4 is a sectional detail showing the relative positioning of the spacer bar contact and 40 of the electrical contact member, and also showing the adjustment bolt for positioning the spacer bar in the spacer side arms;

Fig. 5 is a detail view partly in section showing the locking mechanism for the power 45 control; and

Fig. 6 is a diagrammatic view showing the power control device and the electrical circuit which operates the locking mechanism.

It has been found desirable in textile machinery to position a stop device between the

draft roll and the spindle, so that a slackening in the sliver caused by a breakage adjacent the spindle, or by slipping of the bobbin on the lifter plate, or by a filling of the bobbin and a subsequent enlargement of the sliver 55 entering the spindle, will cause the stop motion to operate. I have devised an improved motion of this type which includes a spacer frame and a spacer bar movably positioned above said frame, the slivers from the draft rolls passing between the spacer bar and frame to the spindles; any abnormal thickening of the sliver due to breakage, to completion 60 of the bobbin winding, or to slackening of the sliver tension, causes the sliver to thicken and kink and press against the spacer bar to operate an electric stop motion; in addition, a slub or other enlargement in the sliver will also actuate the spacer bar when 65 passing thereunder, and thus cause stopping of the machine; and the following detailed description discloses a preferred construction embodying the principles of my invention:

Referring to the drawings, and particularly to Fig. 1, a spindle 10 is rotated through the usual spindle pulley 11, belt 12 and power pulley 13, the spindle having mounted thereon a flier wing 14 and flier 15. Within the flier 15 is positioned a bobbin 16 seated on a friction disk 17 which in turn is mounted on the lifter plate 18, the bobbin being reciprocated along the spindle by means of the usual lifter rack 19 and cooperating lifter pinion 20.

Each sliver 21, in its passage to the bobbin, passes through a first set of draft rolls 22, a comb 23 and a second set of draft rolls which include a lower corrugated roll 24 and an upper pressure roll 25. In the preferred construction, the pressure roll 25 has a separate covering formed by an apron 26 which passes over the pressure roll 25 and an idler pulley or the like 27. Each sliver then passes through a spacer frame 28, over a guide roll 29, and into a spindle 10.

The spacer frame 28, as shown in Figs. 2 and 3, is preferably formed of a rectangular plate or base 30 at the ends of which vertical arms 31 are detachably secured by holding studs 32 or the like. Each arm 31, as clearly

shown in Fig. 4, has a vertical slot 33, the top of the slot being open as at 34 to permit the entrance therein of a reduced portion 35 of a spacer bar or rod 36. The spacer bar 36, as clearly shown in Fig. 2, is bent downwardly toward the base 30, and is adjustably held in desired relative position to the base by bolts 37 which are removably positioned within the slots 33. The spacer bar has a threaded opening 38 at one end within which a screw or the like is removably positioned to form an electrical contact member 39. The arm 31 adjacent the contact member 39 is bored to receive an electrical contact pin 40 to which a lead wire 41 is secured in any desired manner, the contact pin 40 having a slot 42 therein through which a contact member 43 extends, a knurled nut or the like 44 forcing a lock block 45 inwardly within the slot 42 to adjustably lock the contact member 43 in a desired position for engagement by the contact member 39.

The power control mechanism is of a type similar to that disclosed in my co-pending application Serial No. 386,173 filed Aug. 15, 1929, and includes a power pulley 46 and an idler pulley 47 mounted on a common shaft 48, a belt shifter 49 secured to a shift rod 50, and a fixed collar 51 on the shift rod positioned to be engaged by an operating lever 52. The operating lever 52 is pivotally mounted in the machine frame or in a fixed standard, as at 53, and is urged by a tension spring 54, also mounted on the machine frame or on the fixed standard, as at 55, to move so as to force the collar 51, the shift rod 50, and therefore the belt shifter 49, towards the idler pulley. Adjustably positioned on the operating lever 52 is a bracket member 56 which has a bifurcated end 57 within which a latch member 58 is pivotally mounted, a tension spring 59 secured to the bracket and the latch member normally swinging the latch member until a stop 60 engages the under side of the bracket to position the latch member in locking position. A vertically positioned armature casing 61 is removably secured within a bore 62 in a bracket 63 which may be part of the machine frame or may be a separate fixed element; the casing 61 is insulated from the bore by means of insulation 64, and has an armature 65 therein, the windings of the armature being secured to the casing at one end and to a contact pin 66, insulated from the casing, at the other end; the contact pin has a lead wire 67 secured thereto. Within the casing and adjacent the armature core is a gravity responsive armature plate 68, hingedly mounted on a pivot pin 69 secured in the sides of the casing, the plate having a spring leaf or the like 70 for aiding gravity in forcing the plate away from the armature core. Two arms 71 hinged on pivot pins 72 at the lower end thereof, which pivot pins are mounted within the sides of the casing, have

their upper ends lockingly received in aligned notches 73 of the armature plate 68. A catch member 74 is swingingly mounted on a pin 75 secured in the sides of the casing, and has trunnions 76 laterally extending therefrom and normally resting in notches 77 formed in the arms 71; a coil spring 78, mounted on the pivot pin 75, serves to constantly urge catch member 74 towards its lower, locked position. 70

The operation of my improved stop mechanism is as follows: 75

As the sliver or slivers pass through the spacer frame, and a slackening of a sliver caused by breakage, by slipping of the bobbin, by completion of the winding of the bobbin, or for any other reason produces a thickening of the fibre and a kinking of the sliver, particularly if the fibre is of the long fibre, curly or kinky type, the pressure of the thickened sliver on the movable bar 36 swinging the bar so as to engage contacts 39 and 43. The bar 36 also swings to engage these contacts whenever a slub or other imperfection of larger width than the usual sliver thickness passes through the spacer frame. 80 The contacting of members 43 and 39 completes an electric circuit through the operating lever 52, the armature casing 61, the armature 65, the catch member 74, and the latch member 58, causing the armature core to lift 85 the armature plate and release the arms 71, thus permitting the tension of spring 54 to pull the latch member 58 out of engagement with the catch member 74, which is forced upwardly against the tension of the coil 90 spring 78, the arms 71 swinging underneath the armature plate 68. This releasing of the latch member causes the operating lever 52 to engage the fixed collar 51 and shift the belt from the power pulley 46 to the idler pulley 47 to stop the machine. As soon as the catch 95 and latch members are disengaged, the circuit becomes broken, and coil spring 78 forces catch member 74 downwardly, the trunnions 100 105 110 115 120 125 130 135 140 145 150 sliver and moved by an abnormal thickness in the sliver to stop the mechanism.

2. In a gill box, sliver draft rolls, a spindle on which the sliver is wound, stop mechanism intermediate said rolls and spindle including a frame, a spacer bar movably mounted in said frame and provided with a portion normally resting on the surface of the traveling sliver to be engaged and operated by an abnormal thickness in the sliver to close an electric circuit and stop the mechanism.

3. In a gill box, sliver draft rolls, a winding spindle, a stop mechanism intermediate said rolls and spindle a slotted spacer frame, a spacer bar extending across the frame and having its ends movably mounted in the slots therein and having a portion normally resting on the traveling sliver to be moved when engaged by an abnormally thickened portion in the sliver to close an electric circuit to stop the mechanism.

4. In a gill box, sliver draft rolls, a spindle on which the sliver is wound, stop mechanism intermediate said rolls and said spindle including a frame, a feeler member having its ends supported in said frame and its intermediate portion normally resting in engagement with the surface of the sliver, contacts on said frame and on said feeler both in an electric circuit, whereby an abnormal movement of said feeler member may close said circuit to stop the machine.

In testimony whereof I affix my signature.
WALTER J. SCOTT.
